UNITED STATES PATENT OFFICE.

ADOLF BELER, OF PITTSBURGH, PENNSYLVANIA, ASSIGNOR TO BELER WATER HEATER CO., OF PITTSBURGH, PENNSYLVANIA.

WATER-HEATER.

1,032,646.

Specification of Letters Patent. Patented July 16, 1912.

Application filed August 14, 1909. Serial No. 512,922.

To all whom it may concern:

Be it known that I, ADOLF BELER, a citizen of the United States, residing at Pittsburgh, in the county of Allegheny and State of Pennsylvania, have invented a new and useful Water-Heater, of which the following is a specification.

This invention relates to hot water heaters of that class in which the water is heated 10 in a series of coils arranged above a gas burner.

The invention has reference more particularly to the arrangement of the coils, the object being to so arrange the same that the 15 water will be rapidly heated, and to this end there is provided a series of connected coils through which the water flows, one of the coils being located close to the burner. The water enters the coil remote from the 20 burner, and thus receives a preliminary heating, and upon entering the coil close to the burner, is instantaneously heated to the desired degree.

The invention is illustrated in the accompanying drawing, in which,

Figure 1 is a vertical sectional view of the heater, Fig. 2 is a horizontal section on the line 2—2, of Fig. 1, Fig. 3 is a detail sectional view of a thermostat used in connection with the water heater showing part of one coil.

In the drawing, 5 denotes the heater casing, which is supported on legs 6, and contains a gas burner 7, which may be of any structure. The burner is located near the base of the casing and at the top of the casing is an outlet 8 for the smoke and other products of combustion. In the casing 5, directly above the burner 7, and in close proximity thereto, is mounted a double helical coil 9 of tubing which extends at the top and bottom of the coil through the wall of the casing as indicated at 10 and 11, the said ends of the tubing being connected 40 on the outside of the casing to the casing 12 of a temperature regulator, which controls the flow of gas to the burner according to the temperature of the heated water flowing from the heater, whereby the temperature 45 of the water is prevented from rising above a predetermined degree. The regulator may be of any structure adapted for the purpose stated, as for instance, the one

shown in my Patent No. 917,704, dated April 6, 1909.

Within the casing 5, above the coil 9, and arranged concentric thereto, is mounted a series of continuous double helical coils 13 of tubing, the tubing at the top of the casing extending through the wall of the casing, 55 and being connected to the cold water supply pipe 14. The tubing at the bottom of the series extends into the coil 9, and is connected thereto by a suitable coupling 15, the connection with said coil being made midway between the ends thereof. The convolutions at the bottom of the series of coils 13 decrease in diameter so that they may enter the coil 9 as stated.

By the herein described arrangement of 70 coils, it will be seen that the cold water enters the heater at the top, and flows downwardly through the coils 13 to the lower end thereof, where it enters the coil 9. The water circulates through the last mentioned 75 coil, it passing upwardly out of the same from the upper end 10 thereof, into the casing 12, and from the latter back to the coil by the way of its lower end 11. A draw off pipe 16 is connected to the casing 12 which 80 carries the hot water to the place of use. The water, upon passing downwardly through the coils 13, is heated to some degree, and upon entering the coil 9, it is instantly further heated to the desired degree. By 85 thus heating the water before it enters the coil 9, less heat is required to raise its temperature to the required degree, and a saving of gas is therefore effected.

The heater is simple in structure, efficient 90 in operation, and economical in its consumption of gas. A gas burner has been shown, but it will be understood that any other form of burner or heating medium may be employed.

While the water is heating in the coils 9 and 13 but while it is prevented from escaping through the draw off pipe 16 the water will circulate in an upward direction through the coil 9 and enter the upper part of the 100 thermostat casing 12. Said water then descends through the casing 12 and enters the lower portion of the coil 9. Thus a circulation is maintained which will operate the thermostat to cause the same to regulate the 105 flow of gas to the pipe 7. When the water

is permitted to escape through the draw off pipe 16 the first supply will enter the pipe 9 from the pipe 13 and this first supply in turn is circulated through the coil 9 to operate the thermostat as indicated.

What is claimed is:—

The combination with a heater, having a gas supplied burner, a valve to control the supply of gas thereto, and a thermostat located exteriorly of the heater and operably connected to control the gas supply valve; of a water coil located in the heater above the burner, said coil having its upper end communicating with the upper end of said thermostat at the level of the upper end por-

tion of the coil within the heater and its lower end communicating with said thermostat at a lower level, an inlet-coil leading from the top of the heater and connected with the first mentioned coil at a point between the levels of the upper and lower end thereof, and a water draw-off connected to the thermostat.

In testimony that I claim the foregoing as my own, I have hereto affixed my signature in the presence of two witnesses.

ADOLF BELER.
